Primary Examiner—Doris V. Coles**Attorney, Agent, or Firm**—Poms, Smith, Lande & Rose**[57] CLAIM**

The ornamental design of a helmet mount for a night vision device, as shown and described.

DESCRIPTION

FIG. 1 is a side view of a helmet mount for a night vision device affixed to a helmet worn by a human operator and supporting a night vision device. The broken lines are for purposes of illustration only and form no part of the claimed design;

FIG. 2 is a top view of the helmet mount for a night vision device;

FIG. 3 is a front view of the helmet mount for a night vision device;

FIG. 4 is a side view of the helmet mount for a night vision device;

FIG. 5 is a bottom view of the helmet mount for a night vision device; and,

FIG. 6 is a rear view of the helmet mount for a night vision device.
